UNITED STATES PATENT OFFICE

ROBERT T. OSBORNE, OF WARREN, OHIO

AIR OPERATED HORN

Application filed January 21, 1932. Serial No. 587,979.

The invention relates to horns suitable for use on automobiles, for fog horns, and the like, and has for its object the provision of an improved construction of voice member by which voice members of different tone pitches may be substituted to change the tone of the reproduced sound, the invention relating particularly to the construction of the voice member and the means for securing it in the horn.

10 The invention will be described in detail hereinafter and will be found illustrated in the accompanying drawing, in which

Figure 1 is a side view in elevation of an improved horn suitable for use in connection with my invention,

Figure 2 is a top plan view, partly broken away and in section,

Figure 3 is an enlarged sectional view taken on a plane substantially shown by the line 20 3—3 of Figure 2, and Figure 4 is a view in perspective of the reed member.

In the drawing similar reference characters are used to designate corresponding parts throughout the several views.

25 The horn includes a blower which is preferably of the type shown in the drawing and indicated at A having a casing 1 in which is mounted a fan 2 on a shaft 3 driven by a suitable electric motor 4. The casing 1 has an outlet portion 5 to which is removably secured a tubular member 6 by means of set screws or the like 7, the other end of the tubular member 6 is provided with an amplifying member or bell C. The tubular member

35 6 is designed to receive a voice or reed member B having an inclined wall 8 provided with openings therein, and 9 indicates reeds secured to the inclined wall 8, said reeds being arranged opposite the openings in the wall so

40 that they will be agitated by air from the blower fan 2 when in operation. The reed member B is secured in position in the tubular member 6 by means of a threaded bolt or screw 10 that threadedly engages a cross bar

45 11 in the mouth of the outlet portion 5, said bar 11 having its inner edge tapered as shown at 12 so that it offers the least resistance to the emission of air from the outlet opening circulated from the fan 2. The reed member

50 is provided with end walls 13 and a middle

partition wall 14 through which the bolt or screw 10 is secured, said end walls and partition serving to hold the member from vertical movement in the member 6.

The device is adapted for use as a warning horn for motor vehicles, and the like, and the electric current to the motor 4 may be controlled by a suitable switch conveniently located. It will be understood that the voice or reed member B may be quickly removed 60 and replaced by removing the bolt 10 either for repair or for changing the pitch or character of the tone of the horn.

What is claimed is:—

1. A voice or reed member for air operated 65 horns, comprising a member having an inclined wall provided with openings, reeds secured to said wall and arranged opposite said openings, a vertical wall at each end of said member, and a partition intermediate of said 70 walls, said walls and partition being spaced from one another to provide recesses for said reeds.

2. In an air operated horn, a tubular member, a cross bar therein having a threaded opening, an amplifying horn having a tubular extension, means to secure said tubular extension to the tubular member, a reed member in said tubular extension having an opening therein, and a threaded member engaging in the openings in the reed member and the cross bar to hold the reed member in operative position.

In testimony whereof I affix my signature.
